DRAWING APPARATUS

William James Evans, Bulwell, Nottingham,
EnglandApplication June 2, 1937, Serial No. 146,077
In Great Britain June 5, 1936

2 Claims. (Cl. 33—78)

This invention is for improved drawing apparatus such as may be employed by draughtsmen for machine drawing. An object of the invention is to provide apparatus in which, by a simple adjustment, straight lines may be produced at various angles without the use of a protractor, or lines parallel with any angle.

Apparatus according to the present invention comprises a drawing board, a straight edge movable over the face of said board, and means whereby when said two members are assembled in a co-operating position, relative rotation can be effected therebetween. More particularly the apparatus embodies a drawing board having, in combination therewith, a straight edge movable over the paper-receiving surface thereof and a pivotal connection between the board and straight edge whereby relative rotational movement can be effected between the two about an axis normal to the surface of the board or paper-receiving surface.

In a preferred arrangement the drawing apparatus in this invention comprises a base, a circular paper-receiving turntable mounted on said base to rotate about a central axis, a straight edge or T-square extending across the paper-receiving face of the turntable and movable laterally over same, and means for guiding said straight edge in its movement. Preferably there are two parallel guides for the straight edge, and the guide or guides are advantageously provided with a linear scale or scales, while the turntable has associated therewith an angular scale whereby various angular positions of the straight edge on the paper can be obtained.

Other features of the invention are embodied in the construction hereinafter more fully described and set forth in the accompanying claims.

For the purpose of more fully describing the nature of this invention reference will now be made to the accompanying drawings, wherein:

Fig. 1 is a plan of an apparatus in accordance with this invention.

Fig. 2 is an enlarged vertical section on 2—2 of Fig. 1.

Fig. 3 is a sectional plan on 3—3 of Fig. 2.

Fig. 4 is a vertical section illustrating the pivotal mounting of the turntable.

Fig. 5 is an enlarged sectional plan of a device for fixing the turntable from rotary movement, and

Fig. 6 is an enlarged vertical section of a pencil holder fitted to the straight edge, said section being taken on line 6—6 of Fig. 1.

In one method of carrying out the invention as shown in Figs. 1 to 3 of the drawings there is a rectangular base 10 of wood or other suitable material having upstanding peripheral walls 11 whereby the base is of shallow box or tray formation, the four corners of the upstanding walls

being curved at their inner edges so that the interior of the base is circular. Within the recess in said base 10 is mounted a circular turntable 12, the upper horizontal face of which is substantially level with the top face of the upstanding walls 11.

This turntable is mounted to rotate on the base on a central axis, and to this end said turntable has fixed thereon at its centre a short stub axle or pivot 13 which enters a circular upstanding boss 14 on the base 10, there being a roller bearing or the like 15 between the pivot and boss (Fig. 4). On the underside of the turntable there are also a plurality of suitably spaced rollers or runners 16, the bearings 17 for which may be fixed to blocks 18 secured to the underside of the turntable, said rollers 16 running on an annular metal disc 19 screwed or otherwise secured to the base 10. By this means the turntable is free to rotate but is held from rocking movement. On the turntable 12 is adapted to be fixed by any suitable means the drawing paper 20. For example a pair of parallel clamping strips 21 may be provided for the paper, said strips coacting with recesses 22 in the upper face of the turntable and the clamping of the paper being effected by manipulation of headed screws 23 coacting with internally threaded sockets 24 screwed to the underside of the turntable, a coil spring 25 encircling the stem of each screw 23 between a washer 26 and the top face of the socket 24. On releasing the screws 23 the springs 25 press upwardly the clamping strip 21 out of the recess 22 so as to permit of the edge of the paper being inserted beneath the strip, after which the screw is tightened up and the edge of the paper is clamped between the strip 21 and the recess 22.

Other means may, however, be employed for fixing the paper in position on the turntable.

Projecting up at each of two opposite side edges of the base 10 above the walls 11 is a guide 27 for a straight edge, T-square or the like 28. Each guide 27 is adjustably secured in position, and one method of accomplishing this will now be described. An angle bar 29 is screwed to the top face of each of the two opposite side walls 11 of the base or to a plate thereon and within each angle bar is fitted a guide bar 27, said guide bar being secured to the wall 11 by a plurality of screws 30 passing through elongated slots 31 (Fig. 3) in the bar, which slots permit of lateral adjustment of the bar. To effect the lateral ad-

justment a plurality of screws 32 pass through and are freely rotatable within the upstanding flange of the angle bar 29 and have a screwing engagement with the bar 27, there being preferably a disc or washer 33 encircling the screw between the angle bar and the opposing face of the guide bar 27. The straight edge 28 extends between the two guide bars 27, said straight edge having a right angle portion or head 34 at each 60

end thereof, and in order to provide a free sliding movement between the heads 34 of the straight edge and the guide bars 27, said guide bars are provided with projecting ribs 35 which 5 coat with grooved rollers 36 mounted in metal bearings 37 within recesses 38 formed in each head 34 of the straight edge. When, therefore, the straight edge is fitted in position extending across the paper-receiving surface of the turntable 12 the guides 27 are laterally adjusted by releasing the fixing screws 30, rotating the adjusting screws 32 and afterwards tightening up said fixing screws 30.

A linear scale 39 is fitted on the top face of 15 each guide bar 27, the straight edge 28 being provided with suitable indicating pointers or the like 40 coacting with said scales so that the straight edge can be moved laterally over the turntable to a measured distance in either direction.

The turntable 12 is provided at its periphery with an angular scale 41 preferably in the form of a thin annular plate with radiating lines and appropriate numerals, say from 0° to 90° as on a 25 protractor, the arrangement being such that as the turntable is rotated on its central axis the peripheral scale moves relatively to a fixed index mark such as is indicated at 42 in Fig. 1, and lines at varying or different angles can be drawn. 30 For example if a line is drawn along the straight edge with the numeral 0 registering with the index mark 42 and a further line is required to be drawn at say 30° to said first line, then the table is rotated until the numeral 30 registers with the 35 index mark, it being understood that if the table is rotated in one direction the line at 30° is drawn beneath the first drawn line, whereas by rotating the table in an opposite direction the second line is drawn above the first line.

40 In order to hold the turntable from movement a manually operable brake is provided. This brake may comprise a brakeshoe 43 (Fig. 5) coacting with the peripheral edge of the turntable 12 and provided with suitable braking material, 45 said brakeshoe being freely mounted at the end of a screw 44 threaded into an internally screwed sleeve 45 fixed by an attachment plate 46 to one of the walls of the base 10, said screw 45 having a milled head or similar head 47 whereby same is rotated. The arrangement is such that when the 50 screw 44 is rotated in one direction the brakeshoe 43 is pressed into frictional gripping engagement with the periphery of the turntable 12 and when screwed in an opposite direction the 55 brake is released. Advantageously also the brake has associated therewith a headed locking pin 48 which conveniently passes axially through the screw 44 and is adapted releasably to coact with any one of a plurality of suitably spaced holes or 60 notches 49 in the periphery of the turntable 12 or any small attachment plates secured thereto. Advantageously the notches 49 are distributed at intervals of say 45° or 90° around the turntable so that at any one of these positions the turntable can be positively locked by pushing inwardly the pin 48.

If desired, the straight edge 28 may have fitted thereto a holder for a pencil or equivalent drawing or marking instrument. For example, as 70 shown in Fig. 6 a pencil or the like 50 may be

releasably clamped in a holder 51 carried by an angle bracket 52 screwed to the top of the straight edge 28, the fixing and the releasing of the pencil being effected by turning a nut 53 coacting with a screwed stem 54 of the pencil holder. The pencil holder may comprise a member having a pencil-receiving hole therethrough rotatably assembled within a sleeve 55 which also has a hole therethrough, the tightening-up of the nut 53 causing the pencil to be gripped between the 10 sleeve 55 and the holder within said sleeve. It will be appreciated that the pencil may be adjusted to extend either vertically or at a suitable angle. Alternatively, the pencil holder or the like may be mounted to slide or be otherwise adjustable along the straight edge. The mounting of a pencil or the like on the straight edge enables lines to be drawn on the paper by the simple movement of the straight edge over same. Also by suitable adjustment of the pencil and of 15 the straight edge, circles can be drawn on the paper by rotation of the turntable.

A plate or angular bracket 55a is advantageously screwed or otherwise fixed at each corner of the base 10 so as to project up above the base 25 walls 11 and function as stops for limiting the traverse of the straight edge or the like 28.

An electrical lamp may be adjustably incorporated with the apparatus for illuminating the paper at any required position, together with a 30 suitable switch.

Apparatus as above described may be fitted 35 adjustably or otherwise upon a stand, trestle or other support constructed and arranged to enable the drawing board to be tilted to varying angles and to be raised and lowered to different heights.

I claim:

1. Drawing apparatus comprising in combination a relatively stationary base provided with a recess; a circular paper-receiving turn-table rotatably mounted within said recess, and provided with a central pivot, and a plurality of arcuately spaced recesses in its peripheral edge; an anti-friction bearing carried by the base receiving said pivot; spaced parallel guides mounted on and projecting upwardly from said base above the plane of said turn-table; a straight edge extending across the turn-table, provided with antifriction runners having traveling engagement with the inner sides of said guides, said runners normally retaining the straight edge down upon the face of the turn-table; an adjustable mounting for said guides, whereby they may be laterally adjusted toward and away from each other to permit assembly of the straight edge between, and removal of the same from, said guides; linear scales on the guides; an annular scale at the periphery of the turn-table; a manually operable brake arranged to frictionally engage said turn-table; a manually operable locking pin arranged for engagement in said peripheral recesses of the turn-table to positively lock it in various angular positions; and a running bearing between the under side of said turn-table and the base.

2. Drawing apparatus according to claim 1, characterized by the locking pin and the brake being co-axially disposed.

WILLIAM JAMES EVANS. 70
